UNITED STATES PATENT OFFICE.

JACOB A. HILL, OF WINSTON-SALEM, NORTH CAROLINA.

CHAIR.

Application filed January 16, 1922. Serial No. 529,784.

To all whom it may concern:

Be it known that I, JACOB A. HILL, a citizen of the United States, residing at Winston-Salem, in the county of Forsyth and State of North Carolina, have invented certain new and useful Improvements in Chairs; and I do declare the following to be a full, clear, and exact description of the invention, such as will enable others skilled in the art to which it appertains to make and use the same.

This invention relates to an improved chair and it has for its principal object to devise a device of this class which is such in construction that it embodies the features and advantages of both a rocker and a reclining or Morris chair.

An important object of the invention is to generally improve upon convertible chairs of this class by providing one of extreme simplicity and durability which includes among other details, a hinged or pivotally mounted back and a pivoted foot and leg rest, together with novel means between the two for simultaneously moving the latter to operative position when the back is moved rearwardly.

Another and important object of the invention is to provide a chair embodying the aforesaid features, the means for connecting the back and foot rest together embodying a detail which functions both as a shoe and a stop, the same slidably engaging the upper curved side of one of the rockers for automatically accomplishing the desired result.

A still further object of the invention is to provide a chair of this class which embodies together with the parts mentioned, a detachable and adjustable head rest for connection to the pivoted back of the chair, this being advantageous in that it insures comfort to the occupant of the chair when reclining.

Other objects and advantages of the invention will be apparent during the course of the following description.

In the accompanying drawings forming a part of this specification and in which like numerals are employed to designate like parts throughout the same:

Figure 1 is a perspective view of a convertible chair constructed in accordance with this invention showing the position of parts when used as an ordinary rocking chair.

Figure 2 is a central vertical sectional view through Figure 1.

Figure 3 is a view like Figure 1, but showing the chair converted to enable the occupant to recline.

Figure 4 is a central vertical sectional view through Figure 3 with the head-rest removed.

Figure 5 is a detail perspective view of the detachable head rest.

In carrying out the invention, I simply make use of an ordinary rocking chair and equip it with a pivotally mounted back 1 and a similarly mounted combined foot and leg rest 2. It may be mentioned that the side pieces 3 of the back are comparatively long and are fulcrumed intermediate their ends as at 4 to the body portion of the shaft.

As before indicated, novel means is associated with these side pieces and the foot rest for simultaneously moving the latter to operative position when the chair back is swung rearwardly. The means in its preferred form comprises a link 5 which is pivotally connected at one end to the lower end of one of the side pieces 3 being pivotally connected at its opposite end to the intermediate portion of a second link 6. The last named link is pivoted as at 7 to the aforesaid foot rest and the lower end thereof is directed laterally inward as at 8 to provide a combined stop and shoe. By carefully examining the drawings it will be seen that this combined shoe and stop engages the upper curved side of the adjacent rocker

and the latter serves somewhat as a cam so that when the back of the chair is swung rearwardly to exert a forward push on the link 5, the shoe is slid along the rocker in such a way as to elevate the foot rest. It may be stated here that there may be links on both sides of the chair as shown or but on a single side. The description for clearness, is in the singular.

For the purpose of maintaining the parts 1 and 2 immovable when once adjusted, I simply employ a curved toothed bar 9 which is pivotally connected to one of the side pieces of the chair back and has its teeth engaged selectively with the laterally disposed pin 10 secured to one of the arms of the chair.

In order to render the chair comfortable when converted as shown in Figure 3, I prefer to employ a supplemental head rest

11. This head rest simply comprises a longitudinally bowed board 12 against which the head is rested and a pair of spaced end pieces arranged at the ends of this board, 5 these pieces or strips being adapted to rest against the upper portions of the side pieces of the chair back. By directing attention to Figure 5 it will be seen that the strips 13 are equipped with spring tongues or the like 10 14 adapted to extend into recesses 15 formed in the side pieces of the back and be engaged with spring clips or the like 16 which cover the recesses. By reviewing Figure 1 it will be seen that a number of the clips 16 15 are employed to permit the head rest to be adjusted to the desired height to insure comfort.

Assuming that it is desired to convert the chair shown in Figure 1 to the reclining chair illustrated in Figure 3, it is only necessary to disengage the curved rack 9 from the pin 10 and to push the back of the chair 1 rearwardly. This may be done before occupying the chair or may be accomplished 25 when the occupant leans against it. It is obvious that when the chair back is so moved, a forward push is exerted on the links 5 and inasmuch as these are connected with other links 6, the latter are moved in such a way as to simultaneously elevate 30 the rest 2. This elevation of the rest is brought about, as before indicated by the sliding of the laterally directed ends 8 of this link on the upper curved sides of the rockers. The laterally directed ends engage 35 the front legs and thus function as a stop for limiting the pivotal movement of the back and rest. This arrangement is extremely rigid because of the fact that the weight 40 of the feet and legs of the occupant is supported from the rockers through the medium of the links 6.

If it is desired to make use of the head rest 11, it is only necessary to engage the 45 spring tongues 14 carried by the strips 13 with the clips 16.

By carefully considering the description

in connection with the drawings, persons familiar with devices of this class will doubtless be able to obtain a clear understanding 50 of the invention. Therefore, a more lengthy and detailed description is deemed unnecessary.

Since probably the best results may be obtained with the construction and arrangement herein shown and described, this is taken as the preferred embodiment of the invention. However, I wish it to be understood that minor changes coming within the scope of the invention as claimed may be 60 resorted to if desired.

I claim:

1. A chair comprising a seat, supporting legs depending therefrom, connecting members for the legs disposed at the lower ends 65 thereof, a back pivoted to said seat, a leg rest pivoted to the front of said seat, links pivoted to the intermediate portion of said leg rest, the lower ends of said links being directed laterally and forming shoes 70 slidably engaging the aforesaid connecting members, and a connection between the intermediate portions of the links and said back.

2. The structure set forth in claim 1 together with a pivoted rack carried by the back, and a pin with which the teeth of said rack are engaged to hold the aforesaid shoes 75 in different adjusted positions on said connecting members.

3. A rocking chair including a pivoted back, a pivoted foot and leg rest, a link pivotally connected at one of its ends to said back, a second link connected at its outer end to said foot rest, said first named 85 link being pivotally connected to the intermediate portion of said second named link and the latter having its lower end directed laterally inward to provide a combined stop and shoe which slidably engages the upper 90 curved face of the adjacent rocker.

In testimony whereof I have hereunto set my hand.

JACOB A. HILL.
